EXPLOSIVELY DRIVEN STUD WITH KNOCK-OFF HEAD PORTION

Robert Temple, Swissvale, Pa., assignor to Temple Velocity Equipment, Inc., Wilmington, Del., a corporation of Delaware

Application May 13, 1949, Serial No. 92,974

1 Claim. (Cl. 85—28)

1 This invention relates to studs adapted to be driven into objects from explosive-actuated tools. A well-designed explosive-actuated tool has a shoulder in the barrel near its outlet or muzzle for stopping the piston that drives a stud out of the barrel when an explosive charge behind the piston is fired. The principal purpose of the piston is to reduce recoil of the tool as much as possible. It does this by striking the shoulder and thus tending to drive the tool ahead only a moment after the expanding gases in the barrel attempt to drive the tool backward. These two forces, acting in opposite directions, substantially counteract each other so that there is very little recoil. However, in order to obtain this result, it is necessary that the tool be designed with the arresting shoulder the proper distance from the object against which the muzzle is held. If the shoulder is too close to that object, the stud will come to rest without the piston striking the shoulder. This will cause considerable recoil. On the other hand, if the shoulder is too far from the work, the piston will strike the shoulder with a great deal of force because it will not be stopped by the stud coming to rest in the work. In such a case the piston is likely to press itself into the opening beyond the shoulder, as if it were starting to extrude through that opening.

It is not difficult to position the shoulder properly for a stud of a given size and an expected penetration into the object into which it is to be driven. Difficulty arises, however, when the length of the head of the stud is changed, because that will affect the position of the piston relative to the arresting shoulder at the moment the stud comes to rest. Thus, if the head is made shorter than the head for which the tool is designed, it has the same effect as making the shoulder too far from the end of the barrel. If the head is made longer than the standard stud head, it is the same as locating the shoulder too close to the end of the barrel. In the first case, the piston may become jammed in the opening beyond the shoulder, while in the second case there will be too much recoil.

It is among the objects of this invention to provide studs of the type under discussion which have permanent heads of different lengths, but with which the driving piston always travels substantially the same distance through the driving tool barrel.

In accordance with this invention, a stud has an elongated driving head integral with one end of a shank. The opposite end of the shank is pointed. The diameter of the head is reduced

at a predetermined point to weaken it so that the portion of the head between its free end and its weakened point can be knocked off after the stud has been driven into an object by an explosive-actuated tool. The portion of the head remaining after the temporary part has been knocked off will form the permanent head of the stud. Thus, a plurality of studs having driving heads of uniform length can be provided with permanent heads having predetermined lengths differing from one another.

The preferred embodiment of the invention is illustrated in the accompanying drawings, in which Fig. 1 is a vertical section through a driving tool barrel and the objects into which the stud, shown in elevation, is to be driven; Fig. 2 is a side view of the stud after it has been driven; Fig. 3 is a similar view of the stud after the upper end of its driving head has been knocked off; and Fig. 4 is a view similar to Fig. 2, showing a stud with temporary and permanent head portions of different lengths than those shown in Fig. 2.

Referring to Fig. 1 of the drawings, the barrel 1 of the driving tool may be of any suitable form, the one shown being part of the tool disclosed in my copending patent application, Serial Number 34,542, filed June 22, 1948, now Patent 2,479,431, issued August 16, 1948. The barrel is mounted in a barrel guide or sleeve 2 and has a threaded rear end screwed into a breechblock 3. The breechblock is provided with an axial passage 4, through which a firing pin 5 can be projected. The front end of the barrel is formed by a muzzle block 6 provided with an internal shoulder 7 having an inner diameter that is slightly less than the main axial bore 8 through the barrel. The rear end of the axial bore is enlarged slightly to receive a loaded cartridge 9, the rim of which is clamped between the breechblock and the rear end of the barrel. The front end of the cartridge case is compressed around a forwardly tapered rear portion 11 of a one-piece piston, as shown in Fig. 1 and in my copending patent application, Serial Number 43,746, filed August 11, 1948, now abandoned. In other words, the front end of the case is tapered and engages the forwardly converging surface of the piston. The front portion 12 of the piston is cylindrical and fits slidably in the barrel directly in front of the enlarged rear end of bore 8. The cartridge contains the usual charge of powder that is detonated by the firing pin.

Attached to the front of the piston by a separable connection is a metal stud 15 which is to be driven out of the barrel and into the objects

that are to be fastened together by the stud. The connection between the stud and piston preferably is a friction connection, such as is provided by a snug fit between an axial projection 16 on the front end of the piston driven into an axial opening in the rear end of the stud. This connection not only holds the stud and piston together after the cartridge is fired, but it supports the stud in the center of the barrel spaced from the wall of bore 8, because the maximum diameter of the stud is less than that of the piston so that the stud can pass through the muzzle block 6 whose shoulder 7 stops the piston.

The front end of the stud shank is pointed, and the front half of the shank may be knurled so that the stud will have a better grip on the objects into which it is driven. The rear end of the shank is enlarged to form a driving head 17 that generally is considerably longer than the head that it is desired the stud should have after it has been driven. The head preferably is circular in cross section, and it is the rear or free end of the head that is provided with the axial opening in which the projection 16 on the piston is inserted. After the barrel has been loaded with the stud, a metal washer 18 is inserted in a socket 19 formed in the outer end of the muzzle block. When the barrel is held vertical, the washer can be retained in the socket by a little grease first applied to the washer. The washer preferably projects from the socket.

The stud can be used for fastening various objects together, or it can be driven into a single object and its head used for fastening something to it by providing the head with screw threads. In the drawings the stud is shown used for the purpose of fastening a wooden stringer 21 or the like to a concrete foundation 22 or support. The washer 18 is employed to increase the effective diameter of the head of the stud, so as to prevent the head from sinking into the wood. As shown in Fig. 1, the washer in the lower end of the driving tool is placed against the top of the wooden stringer, and then the firing pin 5 is driven down against the cartridge 9 in order to detonate it. The piston and stud will be driven ahead as soon as the gases resulting from the explosion in the cartridge build up a high enough pressure behind the piston to enable its flaring rear end 11 to move forward and expand the reduced front end of the cartridge case into the enlarged portion of the barrel bore. This results in the piston and stud having a high velocity from the moment that they leave the cartridge. The length of driving head 17 is so related to the height of shoulder 7 above the wood that the stud will come to rest in the wood and concrete just as, or slightly before, the piston strikes the shoulder. At practically the same moment that the tool starts to recoil, the shoulder 7 in the recoiling or rising barrel will strike the piston and thus counteract the recoil. This impact also will release the piston from the head of the stud.

It is a feature of this invention that studs, all having driving heads of the correct length for proper operation of the tool, can be provided with permanent heads shorter than the driving heads and differing in length from one another to any desired extent. Accordingly, as 70

shown in Figs. 1 and 2, the diameter of the driving head is reduced, such as by an annular groove 25, at a point spaced from the upper end of the shank such a distance as to provide between that point and the shank a permanent head 26 of the desired length or height. The head is weakened sufficiently to permit the portion 27 of the head between its free end and the weakened point to be knocked off readily after the stud has been driven, thereby leaving only the permanent head as shown in Fig. 3. The weakening of the driving head preferably is accomplished by tapering it toward the shank.

As shown in Figs. 2 and 4, the height of the permanent head will depend upon the length of the knock-off portion, which in turn depends upon the location of the groove 25 that weakens the driving head 17. This groove can be located at any point along the driving head. In every case, however, the length of the driving head is the same so that during driving of the stud objectionable recoil will not occur nor will the piston attempt to squeeze past the arresting shoulder 7 in the muzzle block.

According to the provisions of the patent statutes, I have explained the principle of my invention and have illustrated and described what I now consider to represent its best embodiment. However, I desire to have it understood that, within the scope of the appended claim, the invention may be practiced otherwise than as specifically illustrated and described.

I claim:

35 The combination with a driving tool having a barrel containing an explosive-actuated piston near its inner end and a piston-stopping shoulder near its outer end, of a stud having an elongated cylindrical driving head formed for temporary connection to said piston and integral with one end of a shank that is provided with a pointed piercing end, the head having a greater diameter than the shank and being provided with a peripheral groove at a predetermined point to weaken it, and the diameters of the portions of the head on opposite sides of said groove being the same but the portion of the head between its free end and said weakened point serving only as a temporary head designed to be knocked off after only the shank of the stud has been driven into an object by said piston, whereby the remaining portion of the head is the permanent head of the stud and whereby a plurality of studs with uniform diameter permanent heads having predetermined lengths differing from one another can be provided with cylindrical driving heads of uniform length that will all project substantially the same distance from the object into which such studs are driven.

ROBERT TEMPLE.
